DESIGN FOR A SACHET

Lucie Marie Shover, New York, N. Y., assignor,
by mesne assignments, to Lentheric Incorporated,
New York, N. Y., a corporation of New
York

Application June 11, 1935, Serial No. 57,222

Term of patent 7 years

To all who it may concern:

Be it known that I, Lucie Marie Shover, a citizen of the United States, residing at New York city, in the county of New York and State of New York, have invented a new, original, and ornamental Design for a Sachet, of which the following is a specification, reference being had to the accompanying drawing, forming part thereof.

In the drawing:

Figure 1 is a front view of the sachet showing my new design, the back portion thereof being substantially plain; and

Figure 2 is a diagrammatic view showing the third dimension of the design illustrated in Figure 1 with the ribbon omitted.

The characteristic feature of my design resides in the sachet as shown, comprising a body of oval section, two mutually symmetrical and intersecting ribbons extending obliquely across the lower part of the sachet from opposite sides thereof, a ribbon at the top of the sachet folded to form a handle member and a bow, the loops and free ends of the bow being disposed laterally and symmetrically, and a conventionalized flower at the knot of the bow.

I claim:

The ornamental design for a sachet substantially as shown and described.

LUCIE MARIE SHOVER.
